Elmore Talbert

Attorney

UNITED STATES PATENT OFFICE.

HORACE POWERS, OF MOUNDS, OKLAHOMA.

CHAIN TOOL.

Application filed December 6, 1921. Serial No. 520,230.

To all whom it may concern:

Be it known that HORACE POWERS, a citizen of the United States of America, residing at Mounds, in the county of Creek and State of Oklahoma, has invented new and useful Improvements in Chain Tools, of which the following is a specification.

The object of the invention is to provide a tool for facilitating the tensioning and holding of a cylinder transmission chain during the fastening or locking of the extremities thereof to avoid the inconvenience ordinarily experienced in properly adjusting the chain to avoid lost motion and in positioning the fastening means while the required tension of the chain is maintained; and with this object in view the invention consists in a construction and combination of parts of which a preferred embodiment 20 is shown in the accompanying drawings, wherein:—

Figure 1 is a side view of a chain tool embodying the invention.

Figure 2 is an edge view of the same.

Figure 3 is a transverse section on the plane indicated by the line 3—3 of Figure 1.

The tool is essentially of the pliers or pinchers type having intersecting levers pivotally connected as at 10 and extended 30 in opposite directions therefrom to form the handles 11 and jaw carrying arms 12, upon the latter of which are mounted jaws 13 of a toothed construction adapted especially for engaging the links of a transmission or motion communicating chain of the type indicated under conditions serving to maintain an even tension throughout the width of the chain and thus insure holding the same in the proper position to be permanently connected. In the construction illustrated, each of said jaws consists of a toothed head 13^a having a central stem 13^b which is mounted in a bearing 14 in the end of the arm 12 by which it is carried, so that 40 there is a possibility of rocking or compensatory movement of the jaw with relation to the arm, and so that the jaw will draw evenly upon the chain regardless of the angular swinging movement of the arm by 50 which it is carried.

For locking the levers constituting the pivotal members of the tool in their adjusted positions with the chain with which the jaws are engaged at the proper tension for fastening, there is employed a locking means consisting in the construction illustrated of a ratchet bar 15 pivotally mounted as at 16 upon one of the members for engagement with a tooth 17 on the other member, said ratchet bar being disposed transversely of the handle portions of the members and having the upstanding finger hold 18 to facilitate the disengagement thereof to release the members after the chain has been fastened.

With a tool constructed as indicated the links of the transmission chain adjacent to its extremities may be engaged and drawn together to effect any desired or preferred tension thereof without the risk of twisting or deflecting the chain or causing an unequal strain at opposite edges thereof, and when the desired tension has been secured the members of the tool may be locked to hold the parts in position while the fastening means for the chain are being positioned.

Having described the invention, what is claimed as new and useful is:—

1. A tool for tensioning and holding cylinder transmission chains having pivotally connected members providing oppositely projecting arms and handle portions, and jaws pivotally mounted upon said arms for swinging movement in planes parallel with the plane of movement thereof.

2. A tool for tensioning and holding cylinder transmission chains having pivotally connected members providing oppositely projecting arms and handle portions, and jaws pivotally mounted upon said arms for swinging movement in planes parallel with the plane of movement thereof and provided with series of teeth for engaging links of the chain.

In testimony whereof he affixes his signature.

HORACE POWERS.
